UNITED STATES PATENT OFFICE.

BEN SELWACKI, OF KULPMONT, PENNSYLVANIA.

SHADE-HOLDER.

1,342,070.

Specification of Letters Patent.

Patented June 1, 1920.

Application filed July 5, 1919. Serial No. 308,768.

To all whom it may concern:

Be it known that I, BEN SELWACKI, a citizen of the United States, and resident of Kulpmont, in the county of Northumberland and State of Pennsylvania, have invented certain new and useful Improvement 5 in Shade-Holders, of which the following is a specification.

This invention relates to shade or curtain 10 holders or the like, and has for its object to provide a reliable device, simple in construction and inexpensive in cost of manufacture.

The above and other objects will become apparent in the description below, in which 15 characters of reference refer to like-named parts on the drawings.

Referring briefly to the drawings, Figure 1 represents my device in plan view, as it appears attached to a window sash.

20 Fig. 2 is a front elevational view of the same.

Fig. 3 is a side elevational view of the same.

Referring now in detail to the drawings, 25 the frame of my holder is composed of two similar parts or arms, indicated by the reference numerals 1 and 2, the same being telescopically connected in adjustable relation by means of sleeves 3. Each of said arms 1 and 2 is shaped as illustrated, being provided with outwardly projecting brackets 6. Said brackets are provided with eyes 5 and troughs 4 for the reception of the pin or spindle ends of a shade roll. A looped 30 bracket 7 is secured to each of the arms 1 and 2 in order to retain a curtain pole or the like.

Clamps 13 are secured to the arms 1 and 2 for the purpose of attaching the holder to a 40 window sash 9. Each of said clamps is constructed of a channel piece 12 rigid to the

arm of the holder, and a pair of hooked jaws 8 slidable in said channel. Each of said jaws has a nut 11 integral with its inner end, through which passes a screw 10, pivotally mounted on said arm. On rotation of said screw in one direction, the jaws 8 will spread, and on reverse rotation of the screw, the jaws will close. Thus it is possible to attach the holder to window sashes 50 not only of different widths, but also of different thicknesses.

Having thus described my invention, what I claim as new and desire to secure by Letters Patent, is as follows:

In a device of the class described, a combined curtain and shade holder comprising a horizontal bracket composed of two parts having telescopic connection, means for providing said connection consisting of a sleeve 60 rigid to the inner end of each of said parts and embracing the other part, clamps for attaching the device to a window frame comprising a troughed member rigid to each of said parts, said members extending equally 65 above and below each of said parts, substantially S-shaped clamps slidable in said trough, eyes rigid to the inner ends of said clamps, the interior of said eyes being screw-threaded, and an adjusting screw passing 70 through each pair of said eyes, the ends of said parts being bent first downward and then at right angles to the same and upward, said last named bent portions being provided with troughs and eyes, an upright 75 member rigid to each of said parts near the outer end thereof and being bent in substantially the form of a horizontal S.

Signed at Mount Carmel, in the county of Northumberland and State of Pennsylvania, 80 this 28th day of June, A. D. 1919.

BEN SELWACKI.
